UNITED STATES PATENT OFFICE.

LOUIS NORDQUIST, OF GALETON, PENNSYLVANIA.

AEROPLANE.

Application filed April 3, 1922. Serial No. 549,028.

To all whom it may concern:

Be it known that I, LOUIS NORDQUIST, a citizen of the United States of America, and resident of Galeton, in the county of Potter and State of Pennsylvania, have invented certain new and useful Improvements in Aeroplanes, of which the following is a specification.

This invention relates to aeroplanes, and has for an object the provision of novel means whereby the apparatus may be elevated by the operation of wings or blades, the said elements to be hereinafter referred to as "wings," the said wings being arranged in pairs, and the wings of each pair being alternately operated to assume horizontal and vertical positions, in order that the ascent of the machine will be augmented.

It is an object of this invention further to provide novel means for communicating oscillatory motion to shafts on which the wings are mounted, so that certain pairs of wings may be moved to horizontal positions while other pairs may be moved to vertical positions and vice versa, while the said wings are also being oscillated vertically. While I have referred to the pairs of wings in the plural, it is to be understood that in the manufacture or production of an apparatus embodying the invention, the number of pairs of wings employed will be varied to suit particular requirements, and therefore, applicant does not wish to be held strictly to the embodiment of the invention here described or illustrated.

It is a further object of this invention to produce novel means whereby the wings may be set at certain positions preparatory to their being driven; and the invention also includes novel means for transmitting power to the wing operating mechanism and to a propeller which may be associated with the apparatus.

It is a further object of this invention to produce means by which partial rotary motion will be communicated to the wings, while at the same time, the said wings are oscillated vertically, as stated, and in the provision of means whereby these driving or operating connections are associated with the same source of power.

With the foregoing and other objects in view, the invention consists in the details of construction, and in the arrangement and

combination of parts to be hereinafter more fully set forth and claimed.

In the describing the invention in detail, reference will be had to the accompanying drawings forming part of this application, wherein like characters denote corresponding parts in the several views, and in which—

Figure 1 illustrates a plan view of an aeroplane embodying the invention;

Figure 2 illustrates a longitudinal sectional view of the car, showing the mechanism therein in elevation;

Figure 3 illustrates a sectional view on a line corresponding with the line 3—3 of Fig. 2;

Figure 4 illustrates a sectional view on a line corresponding with the line 4—4 of Fig. 2;

Figure 5 illustrates a sectional view on the line 5—5 of Fig. 2, omitting the wings and parts associated with them;

Figure 6 illustrates a sectional view of the crank shaft, showing the wing operating cams;

Figure 7 illustrates an enlarged detail view of the head of a pitman;

Figure 8 illustrates a sectional view thereof;

Figure 9 illustrates a perspective view of a fragment of the main crank shaft;

Figure 10 illustrates a sectional view of the head of one of the main pitmen;

Figure 11 illustrates a perspective view of one of the wings and its shaft having an arm;

Figure 12 illustrates a detailed view, partly in section, showing the wing rotating pitman;

Figure 13 illustrates a perspective view of an eccentric strap with a crank with which it is associated.

In these drawings 15 denotes a car which may be of any appropriate shape or construction, the same being provided with any suitable number of bearing brackets 16 in which a main crank shaft 17 is journaled, and a plurality of bearing brackets 18 at the sides of the main crank shaft in which crank shafts 19 are journaled.

The crank shaft 17 is provided with eccentrics 20, a pair of which is mounted on the said crank shaft for each pair of wings, and an eccentric strap 21 operates in conjunction with each eccentric. Each eccen-

tric strap has an arm 22 oscillatable on a wrist pin 23 of a crank 24 of a crank shaft 25, the crank shaft also having another crank 26 to which the lower end of the wing oscillating pitman 27 is connected by a ball and socket joint such as 28. The upper end of the wing rotating pitman has a socket 29 to receive the rounded end 30 of the arm 31, which arm is mounted on the shaft 32 of the wing. The inner end of the shaft 32 has a ball 34 which fits in one of the sockets 35 of the wing oscillating pitman 36, it being shown that the lower end of the wing oscillating pitman is mounted on one of the throws of the crank shaft 17, in order that the wing oscillating pitman rises and falls as the crank 17 is rotated. As the wing oscillating pitman has two sockets, it follows that the wings of each pair are operated simultaneously, while the shafts are oscillatable on their fulcrums which, in the present embodiment of the invention, comprise the posts 37, which posts have bearings for the enlarged portion 38 on the shafts of the wings. The shafts of the wings not only oscillate in the bearings of the posts, but they partially rotate therein while the wings are being shifted from the horizontal to the vertical positions during the operation of the apparatus.

It is the purpose of the inventor that the relation of parts shall be such that when the inner ends of the shafts of the wings are in their lowermost positions, the shafts of the wings will have been rotated so that the wings are in horizontal positions and elevated with respect to the inner ends of the shafts, and as the inner ends of the shafts are driven upwardly the wings will exert force to raise the machine, it being understood that other wings are in vertical position in order that they will offer a minimum resistance to the action of the lifting wings, and that thereafter, the former vertically disposed wings will be turned to horizontal positions after they have been elevated, and so the pairs of wings will operate successively to produce a lifting action during the rotation of the crank shaft.

A toothed wheel 39 is secured on the crank shaft, and a handle 40 is oscillatable thereon and provided with a detent 41 pivoted to engage the teeth of the wheel when the handle is moved in one direction, in order that it will be effective to partially rotate the crank shaft, the said detent being free to ride over the teeth when the handle is moved in the opposite direction. This handle is provided for the purpose of permitting the crank shaft to be rotated to set the wings at proper starting positions, or for other purposes.

The motor 42 is here conventionally shown and it may be of any appropriate type. Its drive shaft 43 may be geared to the shaft

44 suitably journaled in the car, and the said shaft 44 has clutch elements 45 and 46 on its ends. The crank shaft has a clutch element 47 which is adapted to be thrown into and out of engagement with the clutch element 46 when the crank shaft is to be driven, and the clutch element 47 is under control of a shifting mechanism 48 which may be manipulated and held at different positions of adjustment by a rack and pawl, generally identified by the numeral 49.

A propeller shaft 50 is journaled in suitable manner and has a propeller 51 which may be used to drive the aeroplane in known manner. The propeller shaft has a clutch member 52 adapted to coact with the clutch member 45 so that it can be coupled to the shaft 44 through the operation of the shifting mechanism 53. This shifting mechanism may be of appropriate type and need not, it is thought, be described in detail.

As a description of the elements of the device and their relation to other elements of the device have been stated in connection with a description of the elements, a résumé of the operation of the apparatus as a whole is believed to be unnecessary for an understanding thereof by one skilled in the art.

I claim:

1. In a flying machine, a car, a crank shaft journaled therein, pairs of eccentrics on the crank shaft, eccentric straps engaging the said eccentrics and having arms extending oppositely, a crank partially rotated by each of the said arms, pitmen connected to the cranks and reciprocated thereby, shafts having wings mounted for oscillatory and rotary motion with respect to the car, arms extending from the said shafts to which the pitmen are connected, a pitman to which the inner ends of the shafts are connected, and means for connecting the opposite ends of the pitman to one of the throws of the crank shaft and means for driving the crank shaft.

2. In a flying machine, a car, a crank shaft journaled therein, pairs of eccentrics on the crank shaft, eccentric straps engaging the said eccentrics and having arms extending oppositely, a crank partially rotated by each of the said arms, pitmen connected to the cranks and reciprocated thereby, shafts having wings mounted for oscillatory and rotary motion with respect to the car, arms extending from the said shafts to which the pitmen are connected, a pitman to which the inner ends of the shafts are connected, and means for connecting the opposite ends of the pitman to one of the throws of the crank shaft, manually operated means for moving the crank shaft to adjust the wings to starting positions, and means for driving the crank shaft.

LOUIS NORDQUIST.
